(57) **CLAIM**

The ornamental design for a gate, as shown and described.

DESCRIPTION

FIG. 1 is a front perspective view of a gate according to a first embodiment, without a flap.

FIG. 2 is a front elevational view of the gate shown in FIG. 1.

FIG. 3 is a rear elevational view of the gate shown in FIG. 1.

FIG. 4 is a left side elevational plan view of the gate shown in FIG. 1.

FIG. 5 is a right side elevational plan view of the gate shown in FIG. 1.

FIG. 6 is a top plan view of the gate shown in FIG. 1.

FIG. 7 is a bottom plan view of the gate shown in FIG. 1.

FIG. 8 is a front perspective view of a gate, according to a second embodiment, with a flap, wherein the flap is in a closed position.

FIG. 9 is a rear perspective view of the gate shown in FIG. 8; and,

FIG. 10 is a rear perspective view of the gate shown in FIG. 8, wherein the flap is in an open position.
